HAT RETAINER

Martin L. Nattenheimer, Chicago, Ill.

Application November 20, 1944, Serial No. 564,189

3 Claims. (Cl. 132—58)

This invention relates to a hat retainer for maintaining hats in position on the head of a wearer. The invention in particular is applicable to women's hats and may be used not only for retaining the hat in position but also for providing desirable ornamentation. The invention in general provides a pair of spring rings one of which may be in the hat while the other may press against the head of a wearer, so that the entire assembly tends to grip the head tightly enough to maintain the hat in position.

In the drawing, Figure 1 shows the invention applied to a hat being worn. Figure 2 shows the spring rings disassociated from the hat.

Referring first to Figure 2, an elongated spring wire may have one end formed as coil spring 10. The wire from coil spring 10 continues to form half loop 11 going to pivot portion 12 and thence continuing to form closed loop 13. Loop 13 has portion 14 formed as a coil spring and continues to form half loop 15 and has end portion 16 formed as a coil spring around the wire of half loop 11. It will be noted that pivot portion 12 of loop section 11 is threaded through coil spring 14 so that in effect, loop 13 and loop 11—15 may be sprung to either increase or decrease the opening between the two loops. The end portions of each of loop halves 11 and 15 are threaded through coil springs 16 and 10 respectively. It is preferred to wind coil springs 10 and 16 tightly enough so that friction will maintain the parts in position.

Loop halves 11 and 15 may be sewed into any desired hat 20 while loop 13 may be covered with

any material for ornamentation. The tendency of the two loops to close on each other as shown in Figure 2 will cause loop 13 to hug the head of a wearer and thus seat hat 20 firmly on the head. Bows or other ornamentations may be attached to loop 13 as desired.

It is possible to make the two loops of two lengths of spring wire and provide suitable anchoring means for the wire ends where size adjustment is made. However, by virtue of the construction shown, only one single length of wire need be used and this may be formed as a general figure 8 and then bent to shape.

What is claimed is:

1. A hat retainer comprising a length of spring wire shaped to form a pair of loops, said two loops having a common region as in a figure 8, one of said loop sections being coiled to form a spring with the other loop section threaded therethrough, one loop being adapted to be fastened to a hat and the other loop being adapted to rest against a wearer's head, said two loops tending to close on each other to retain the hat on a wearer.

2. The structure of claim 1 wherein the hat retaining loop has one portion thereof formed as a coil spring and the other portion threaded therethrough to permit adjustment for size.

3. The structure of claim 1 wherein the hat retaining loop has two end portions formed as coil springs with the straight part of one end threaded through the coil spring of the other end for permitting adjustment for size.

MARTIN L. NATTENHEIMER.
